UNITED STATES PATENT OFFICE.

H. N. GALLAGHER, OF GENEVA, NEW YORK.

IMPROVEMENT IN HEEL-FASTENINGS FOR SKATES.

Specification forming part of Letters Patent No. 43,486, dated July 12, 1864.

To all whom it may concern:

Be it known that I, H. N. GALLAGHER, of Geneva, in the county of Ontario and State of New York, have invented certain new and useful Improvements in "Heel-Fastenings for Skates;" and I do hereby declare that the following is a full, clear, and exact description thereof, reference being had to the accompanying drawings, making a part of this specification, in which—

Figure 1 is a top view of a skate with my invention applied. Fig. 2 is a side elevation of the rear end of the same. Fig. 3 is a front end view of Fig. 2. Fig. 4 is a top view of another modification of the clamp *b*, which is pivoted to the foot piece, and has but one clamping-screw. Fig. 5 is also a top view of still another modification of the clamp. Fig. 6 is a vertical section of Fig. 5, and showing a portion of the foot-piece.

Similar letters of reference indicate corresponding parts in the several figures.

To enable others to make and use my invention, I will describe its construction and operation.

The shank of the crescent shaped plate *d* is let into the foot-piece and secured to it by a screw or otherwise. The inner surface of the plate is roughened, as shown in Fig. 1. The plate *b* is attached to the foot-piece *F* by screws through its shank *c*. Plate *b* has two projecting wings, through which the screws *s* operate. Each of these screws is provided with a pivoted clamping plate, *a*, which also has a roughened face.

The skate is applied to the boot by placing the heel between the plates *a* and *d* and then turning up the screws *s* by means of the key or pin *p*, the screw-heads, each being perforated with two holes, drilled at right angles with each other.

Fig. 4 represents such a modification of the plate *b* as requires but one clamping-screw, the shank of the plate being pivoted to the foot piece *F*, so that when the screw *s* is turned up to press the plate *a* against the heel that end of the plate *b* is moved back

until the oval faced plate *a'* also strikes the heel, as indicated by the red lines. This variety may be made in pairs, if desired.

Figs. 5 and 6 represent still another variety or modification. In this the plate *b* is roughened on its face and becomes the clamping-plate. Its shank *c* is slotted to receive the shank of the binding-screw *g*, to which the eccentric hollow head *f* is pivoted. This head is provided with a flange on its upper side, which has several notches, *i*, to receive a small key or lever to turn it by; and, as it just fits between the projecting ears or lugs *e*, cast upon the shank *c* of plate *b*, when the head *f* is turned it carries the plate forward, as indicated by the red lines. The web *h*, being let into a groove in the foot-piece *F*, causes the plate to preserve its direction. Either of these modifications are applicable to almost every variety of skate in use.

By my method of clamping a considerable portion of the heel is received between the clamping-plates, whereby the "lifts" of the heel will never be torn off, as they are liable to be when the ordinary sharp points or spurs are used; besides, the roughened clamping-plates which I use are applicable to any boot without any preliminary preparation, such as making notches in the heels or attaching notched plates or devices thereto, which I am aware has heretofore been done. Besides, by my construction and arrangement of the parts, the clamping-screw or screws are placed under the hollow of the boot, and therefore can never catch against anything so as to trip the skater, which is of great importance to him.

What I claim as my invention, and desire to secure by Letters Patent, is—

The plate *b*, provided with one or more clamping-screws, *s*, and plates *a*, in combination with the crescent plate *d*, when they are constructed, arranged, and operate conjointly, in the manner and for the purpose described.

H. N. GALLAGHER.
